UNITED STATES PATENT OFFICE

2,385,191

ELECTRICAL CONNECTOR

Henry E. Brunelle, Jr., Schenectady, N. Y., assignor to General Electric Company, a corporation of New York

Application December 31, 1942, Serial No. 470,760

4 Claims. (Cl. 174—35)

My invention relates to electrical connectors formed as an elbow for ignition systems and particularly to such elbow connectors as are used for connecting spark plug electrode terminals to distribution leads of the system.

An object of my invention is to provide an improved elbow connector for electrical systems having substantially non-inductive resilient terminal elements.

Further objects and advantages of my invention will become apparent and my invention will be better understood from the following description referring to the accompanying drawing, and the features of novelty which characterize my invention will be pointed out with particularity in the claims annexed to and forming part of this specification.

The drawing illustrates an embodiment of my improved elbow connector, partly in section, as applied to an ignition system.

In this arrangement a spark plug having a barrel 10 with an upper threaded portion 11 and a central discharge electrode 12 is arranged to be connected to a distribution lead conductor 13 through an elbow connector constructed in accordance with an embodiment of my invention. In high frequency ignition systems, it is particularly desirable that the ignition system conductor should be thoroughly shielded and that these shielding elements should be adequately grounded to prevent interference with other high frequency apparatus, such as radio equipment, in the vicinity of the ignition system. Furthermore, it is desirable that the relatively high temperature spark plug unit should be thermally isolated to a certain degree from the distribution conductor in order to prevent too rapid or undue deterioration of insulation about the distribution conductor. The provision of an elbow connector such as that shown in the drawing effectively provides these desirable features. In the arrangement, the connector is formed as an elbow having a pair of arms extending at an angle to each other which is determined by the location of the spark plug relative to the distribution harness and the distribution conductor lead. This elbow connector is provided with an outer shield 14 of electrically conductive material which is formed with a shoulder 15 at one end thereof about which a nut 16 is arranged with an in-turned flange 17 extending about the inner edge of the shoulder 15. This nut 16 is adapted to engage the threaded end 11 of the spark plug barrel 10 and to draw up the shoulder 15 of the connection elbow shield 14 securely against the upper

edge of the spark plug barrel, thereby rigidly securing the elbow connector to the spark plug. An insulating lining is arranged within the outer shield member 14 and is formed of a pair of oppositely extending liner members 18 and 19 with the inner ends 20 thereof formed at complementary angles to provide a snug fit within the outer elbow shield 14. Central openings 21 and 22 are formed through the insulating liner members 18 and 19 and enlarged central openings 23 and 24 extend inwardly from the outer ends of the insulating liners 18 and 19, respectively. An electrical conductor element 25 extends through the central openings 21 and 22 in the insulating liners and the ends thereof extend through openings 26 and 27 in the closed sides of cup-shaped substantially non-inductive terminal members 28 and 29, respectively. These cup-shaped members form electrically conductive outer casings for resilient terminal members and are electrically connected to the ends of the electrical conductor 25 in any suitable manner as by soldering. These resilient terminal members are arranged within the enlarged central openings 23 and 24 of the insulating liners and are of a size such that the outer ends of the insulating liner members 18 and 19 and adjacent ends of the outer shield 14 extend axially thereof substantially beyond the outer ends of the terminal members 28 and 29 to provide for the insertion of external contact elements. The resilient terminal members include contact caps 30 and 31 arranged axially slidably within the cup-shaped members 28 and 29 and are biased by compression springs 32 and 33 outwardly towards the open end of the cup-shaped members. The springs and the contact caps are retained within the cup-shaped members by inturned outer edges 34 and 35 of the cup-shaped members and thus are provided with an electrical shield which extends about the springs and the contact caps for minimizing the mutual inductive effect of electrical current through these springs with elements externally of the terminal members. An electrical connection is provided between the spark plug central electrode 12 and the distribution conductor lead 13 through the elbow connector by contact of the upper end of the central electrode 12 with the contact cap 30 when the connector nut 16 is securely drawn up on the end of the spark plug barrel 10. As shown in the drawing, the end of the spark plug electrode 12 depresses the contact cap 30 against the action of the spring 32 to provide a good electrical contact therewith, thereby forming an electrical circuit with the conductor

25 and the resilient terminal element which includes the cup-shaped member 29, the spring 33, and the contact cap 31. This contact cap 31 is adapted to be depressed against the action of the spring 33 by engagement with a terminal 36 formed on the end of the distribution conductor 13 over an insulating cap or bushing 37 which extends about the inner end of insulation 38 around the distribution lead conductor 13. This terminal element 36 is held in engagement with the contact cap 31 by a nut 39 which threadedly engages the adjacent threaded outer end 40 of the outer shield 14 of the elbow connector. This nut is provided with an inwardly extending shoulder 41 arranged about an outwardly extending shoulder 42 on a bushing 43 secured to a metallic shield 44 arranged about the distribution conductor 13. The adjacent outer end 43 of the elbow outer shield 14 is turned inwardly over the outer edge of the insulating liner 19, such that when the nut 39 is drawn up tightly about the threaded end 40 of the shield 14, a good electrical contact is provided between the inturned end 45 of the elbow shield and the distribution shield bushing 43, thereby assuring good electrical contact and grounding of the interconnected shields 44 and 14 and the grounded spark plug barrel 10.

The elbow connector shown in the drawing can readily be assembled by soldering or upsetting one end of the conductor 25 in one of the cup-shaped terminal members, inserting the spring and contact cap in this cup-shaped terminal member and then spinning over the outer edge to retain the cap and spring in position. The conductor 25 and the assembled resilient terminal may then be inserted in one of the insulating liners, and this assembly inserted into the elbow shield 14. The other insulating liner then may be inserted in the other end of the elbow shield 14 with the conductor 25 extending through the central opening in this latter insulating liner, after which the second cup-shaped terminal member may be secured to its respective end of the conductor 25. A spring and contact cap then can be placed in this latter cup-shaped member and the outer edge thereof may be spun over to form the inturned flange or lip for retaining the cap and spring in assembled relationship in the terminal member. This provides a simple construction which may be readily assembled from standard parts and provides for a good electrical contact of substantially non-inductive resilient terminal elements with the respective contacts of the cooperating parts of an electrical system.

While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States is:

1. An elbow connector for an ignition system having a pair of arms extending at an angle to each other and including an outer shield of electrically conductive material about said arms, a lining of insulating material arranged within said outer shield and having a central opening therein, a resilient terminal member arranged in each end of said central opening in said insulating lining including a cup-shaped member of electrically conductive material, means including an

electrical conductor extending through said central opening in said insulating lining secured to each of said cup-shaped members for securing said cup-shaped members in position and for electrically connecting together said cup-shaped members, a contact cap axially slidable within said cup-shaped member, means for retaining said contact cap in said cup-shaped member, a compression coil spring within said cup-shaped member arranged to bias said cap outwardly of said cup-shaped member, said cup-shaped member providing a shield about said spring for minimizing the external inductive effect of electric current through said spring, and means for electrically connecting said outer shield to cooperating shields of other system members at each end of said connector.

2. An elbow connector for an ignition system having a pair of arms extending at an angle to each other and including an outer shield of electrically conductive material about said arms, a pair of oppositely extending liner members of insulating material arranged within said outer shield and having a central opening therein, a resilient terminal member arranged in each outer end of said central opening in said insulating liners including a cup-shaped member of electrically conductive material, means including an electrical conductor extending through said central opening in said insulating liners secured to each of said cup-shaped members for securing said cup-shaped members in position and for electrically connecting together said cup-shaped members, a contact cap axially slidable within said cup-shaped member, a compression coil spring within said cup-shaped member arranged to bias said cap outwardly of said cup-shaped member, said cup-shaped member providing a shield about said spring for minimizing the external inductive effect of electric current through said spring and having an inturned outer edge for retaining said cap in said cup-shaped member.

3. An elbow connector for an ignition system having a pair of arms extending at an angle to each other and including an outer shield of electrically conductive material about said arms, a pair of oppositely extending liner members of insulating material arranged within said outer shield and having a central opening therein with an enlarged central opening adjacent the outer end of each of said insulating liners, and a resilient terminal member arranged in each of said enlarged openings in said insulating liners including a cup-shaped member of electrically conductive material, means including an electrical conductor extending through said central openings in said insulating liners secured to each of said cup-shaped members for securing said cup-shaped members in position and for electrically connecting together said cup-shaped members, a contact cap axially slidable within said cup-shaped member, a compression coil spring within said cup-shaped member arranged to bias said cap outwardly of said cup-shaped member, said cup-shaped member providing a shield about said spring for minimizing the external inductive effect of electric current through said spring and having an inturned outer edge for retaining said cap in said cup-shaped member, each of said insulating liners and said outer shield being formed to extend axially substantially beyond said terminal members at the outer ends thereof.

4. An elbow connector for an ignition system having a pair of arms extending at an angle to

each other and including an outer shield of electrically conductive material about said arms, a pair of oppositely extending liner members of insulating material arranged within said outer shield and having a central opening therein with an enlarged opening adjacent the outer end of each of said insulating liners, a resilient terminal member arranged in each of said enlarged openings in said insulating liners including a cup-shaped member of electrically conductive material, means including an electrical conductor extending through said central openings in said insulating liners secured to each of said cup-shaped members for securing said cup-shaped members in position and for electrically connecting together said cup-shaped members, a contact cap

5 axially slidable within said cup-shaped member, means for retaining said contact cap in said cup-shaped member, a compression coil spring within said cup-shaped member arranged to bias said cap outwardly of said cup-shaped member, said cup-shaped member providing a shield about said spring for minimizing the external inductive effect of electric current through said spring, each of said insulating liners and said outer shield being formed to extend axially substantially beyond said terminal members at the outer ends thereof, and means for electrically connecting said outer shield to cooperating shields of other system members at each end of said connector.
